UNITED STATES PATENT OFFICE.

EUGENE L. BUTTON, OF BROOKLYN, NEW YORK.

DESIGN FOR A PACKING-CAN.

SPECIFICATION forming part of Design No. 22,664, dated August 1, 1893.

Application filed May 24, 1893. Serial No. 475,379. Term of patent 14 years.

To all whom it may concern:

Be it known that I, EUGENE L. BUTTON, a citizen of the United States, residing at Brooklyn, in the county of Kings and State of New York, have invented and produced a certain new and original Design for Packing-Cans, of which the following is a full, clear, and exact description.

The object of this invention is to provide a safety package for tourists and others for containing a bottle of liquid shoe dressing, although, as is obvious, the packing can herein set forth may be used for other purposes.

The leading features of the design are a cylindrical metallic can supplied with a spirally convoluted mouth, having at its base a circumferential outwardly-projecting bead, and supplied with a spirally convoluted cover, the upper surface of which is composed of superposed annular projections, the central one of which is in the form of a bead surrounding a flat cavity, the outer projections being approximately segments of ellipses in cross-section.

In the accompanying drawings illustrating my design, in the several figures of which like parts are similarly designated, Figure 1 is an elevation, Fig. 2 a central vertical section, and Fig. 3 a top plan view.

The letter *a* designates the body of a cylindrical metallic can, and *b* the bottom thereof.

The mouth of the can is spirally convoluted as at *c*, and below this mouth is the circumferential, outwardly-projecting bead *d*. The cover is spirally convoluted, as at *e*, corresponding with the spirally convoluted mouth of the body of the can, and the upper surface of such cover is broken up with superposed annular projections, *f*, *g*, *h*, and the depressed or flat center *i*. As will be observed, the annular projection *h* is in the form of a bead, and the flat bottomed cavity *i* is inclosed by said bead. The projections *f* and *g* are approximately of the form of segments of ellipses in cross-section, as seen in Fig. 2. It will be observed that the cover itself is of greater diameter than the mouth of the body portion, but the circumferential bead *d* overcomes the appearance of top-heaviness, which otherwise would be observable. The projections on the cover break up the surface of such cover, and thus destroy any otherwise apparent flatness therein.

What I claim is—

The design for a packing can, substantially as herein shown and described.

In testimony whereof I have hereunto set my hand this 23d day of May, A. D. 1893.

EUGENE L. BUTTON.
